HEATING UNIT FOR HAIR CURLING CLAMPS

Henricus Franciscus Theresia Schellens, Drachten, Netherlands, assignor to North American Philips Co., Inc., New York, N.Y., a corporation of Delaware

Filed Feb. 23, 1967, Ser. No. 5,931

Claims priority, application Switzerland Sept. 5, 1966

Term of patent 14 years

(Cl. D86—10)

FIG. 1

FIG. 2

FIG. 3

FIG. 4

FIG. 5

FIG. 6

FIG. 7

FIG. 8

FIG. 1 is a perspective view of the heating unit for hair curling clamps showing my new design in the closed position;

FIG. 2 is a perspective view thereof with cover and clamp removed;

FIG. 3 is a left side elevational view in the condition of FIG. 2, with the upper button thereof being deleted;

FIG. 4 is a right side elevational view thereof;

FIG. 5 is a front elevational view;

FIG. 6 is a rear elevational view;

FIG. 7 is a top plan view in the condition of FIG. 2;

FIG. 8 is a bottom plan view.

I claim:

The ornamental design for a heating unit for hair curling clamps, as shown.
